S. F. BORKEY

REFRIGERATING APPARATUS

Filed Jan. 24, 1924

Stephen F. Borkey

UNITED STATES PATENT OFFICE.

STEPHEN F. BORKEY, OF DETROIT, MICHIGAN.

REFRIGERATING APPARATUS.

Application filed January 24, 1924. Serial No. 688,116.

To all whom it may concern:

Be it known that I, STEPHEN F. BORKEY, a citizen of the United States of America, residing at Detroit, in the county of Wayne 5 and State of Michigan, have invented certain new and useful Improvements in Refrigerating Apparatus, of which the following is a specification, reference being had therein to the accompanying drawing.

10 This invention relates to refrigerating apparatus and relates more particularly to apparatus for household refrigeration.

It is usual, in artificial refrigeration, to provide a pipe or pipes within which the 15 refrigerating medium circulates, absorbing heat from the medium surrounding said pipes, which medium is usually a liquid of low freezing point, as brine or a solution of alcohol.

20 The present invention consists in the novel unitary relation of such a system of pipes to a common supply header, more particularly when said header is further a boiling chamber for the refrigerating medium.

25 Further, the invention consists in the particular arrangement of said system of pipes within a tank containing a liquid of low freezing point, and in the specific location upon said tank of the boiling chamber.

30 Said invention is illustrated in a preferred form in the accompanying drawing, wherein:

Figure 1 is an end view of the improved apparatus, partly in section, the plane of 35 section being indicated by the line 1—1 of Figure 2.

Figure 2 is a longitudinal vertical sectional view of the same, taken upon line 2—2 of Figure 1.

40 In these views, the reference character 1 designates a rectangular tank, formed preferably of sheet copper, and receiving a liquid of low freezing point, as, for example, a solution of alcohol. 2 and 3 are chambers 45 opening into said tank through one of the vertical walls thereof, spaced preferably one above the other, and serving to increase the surface area of the tank, thus promoting the absorption of heat by the liquid in the tank, and serving also, if desired to receive 50 foods or liquids to be cooled. On the tank 1 there is mounted a boiling chamber 4, preferably of cylindrical form. The lower-most portion of said chamber is of a trough 55 or channel shape, as indicated at 5, this por-

tion extending the full length of said chamber and depending into the tank 1 through the top thereof. A rigid sealed joint is formed between the top of the tank and said boiling chamber, as for example, by soldering, designated at 6. The chamber 4 is a receiver for a refrigerant, usually a liquid of low boiling point, as for example, sulphur dioxide. 7 designates the surface level of this liquid, and further designates the bottom level of a quantity of light oil, which floats upon the refrigerant. Upon said oil rides a ball float 8, which is secured to a stem 9, pivoted at 10, and controls a needle valve 11, which in turn controls a restricted inlet 12 for the refrigerant. Said inlet is arranged preferably below the normal level of the refrigerant. 13 designates two sets of pipes which connect with the trough 5 through opposite walls thereof, extending oppositely from said trough in the upper portion of the tank 1, and downwardly at opposite sides of the chambers 2 and 3, right angle bends being formed between the oppositely and downwardly extending portions 80 of said pipes. Adjacent the bottom of said tank, each of said sets of pipes communicates with a horizontal header, such as is indicated at 14.

In the operation of the described apparatus, as long as the temperature of the liquid in the tank 1 is higher than the boiling point of the refrigerant in the chamber 4 and pipes 13, said refrigerant will continue to boil or gasify, bubbling up through said pipes and through the refrigerant and oil in the chamber 4, to the upper port portion of said chamber. The liquid level in the latter is lowered by this generation of gas, and the float 8 consequently acts upon the valve 11 to open the same, admitting more of the liquid refrigerant and restoring the normal level, at which the float closes the needle valve. An outlet 15 communicating with the upper portion of the chamber 4 is 95 adapted to deliver the gas therefrom to the usual compressor (not shown).

The described unit is of simple and compact construction, easily assembled, and highly efficient in effecting a transfer of 105 heat from the liquid in the tank 1 to the refrigerating medium. A highly important feature of the invention is the provision of the headers 14 connecting the lower ends of the pipes 13, said headers being of a larger 110

diameter than said pipes, and acting to locate a considerable body of the refrigerant adjacent the bottom of the tank, taking care of the heat transferred to the liquid in the tank through the bottom of the latter. A further advantage of said headers lies in the provision which they make for a discharge of gas from the lower end of any pipe 13 to the adjacent pipes, in case some 10 obstruction becomes lodged in the first-mentioned pipe. Said headers 14 also tend to maintain uniformity of temperature of the refrigerant in the several pipes 13 by permitting a circulation between the lower 15 ends thereof.

What I claim is:

1. A refrigerant receiving unit comprising a boiling chamber having an integral trough portion of reduced width depending therefrom, two sets of spaced pipes communicating with said trough portion, oppositely laterally extending therefrom and downwardly extending in spaced relation, and headers respectively connecting the lower 25 ends of said pipes.

2. A refrigerating apparatus comprising a tank for receiving a liquid to be cooled, a boiling chamber for a refrigerant surmounting said tank and having a trough portion depending within said tank, two sets of pipes communicating with said trough portion and oppositely laterally extending therefrom, and downwardly extending in spaced relation, and headers respec-

tively connecting the lower ends of said sets 35 of pipes.

3. A refrigerating apparatus comprising a tank for receiving a liquid to be cooled, said tank having an air chamber therein intermediate of its height, a boiling chamber for a refrigerant surmounting said tank, two sets of pipes communicating with the lower portion of said boiling chamber and depending within said tank at opposite sides of said air chamber, and headers respectively connecting the pipes of said sets within the lower portion of said tank.

4. A refrigerating apparatus comprising a tank for receiving a liquid to be cooled, a boiling chamber for a refrigerant surmounting said tank, two sets of pipes communicating with said boiling chamber and oppositely laterally extending therefrom within said tank and having portions extending downwardly in spaced relation, and headers respectively connecting the lower ends of said sets of pipes.

5. A refrigerating apparatus comprising a tank for receiving a liquid to be cooled, a boiling chamber for a refrigerant surmounting said tank and having a trough portion depending within said tank, a set of pipes communicating with said trough portion and having portions downwardly extending within said tank, and a header connecting the lower ends of said pipes.

In testimony whereof I affix my signature.
STEPHEN F. BORKEY.
